United States Patent Office.

DAVID MANUEL, OF BOSTON, MASSACHUSETTS, ASSIGNOR TO HIMSELF
AND WILLARD MANUEL, OF SAME PLACE.

Letters Patent No. 63,066, dated March 19, 1867.

IMPROVED BED BOTTOM.

The Schedule referred to in these Letters Patent and making part of the same.

TO ALL WHOM IT MAY CONCERN:

Be it known that I, DAVID MANUEL, of Boston, in the county of Suffolk, and State of Massachusetts, have invented a new and useful improvement in Spring Beds; and I do hereby declare that the following is a full, clear, and exact description thereof, which will enable others skilled in the art to make and use the same, reference being had to the accompanying drawings, forming part of this specification, in which—

Figure 1 is a longitudinal vertical section of the spring bed, showing my improved form and arrangement of the springs for suspending the slats.

Figure 2 is a top view of a bed with my improved springs.

Figure 3 is a detached view on the under side of the slat.

Similar letters of reference indicate like parts.

This invention relates to improvements in the construction and arrangement of a spring bed, and consists in a new mode of forming the springs and connecting them to the slats and bedstead, which secures an easy and gentle pliability and elastic power in the springs.

A represents a bedstead, and B the slats, made in the usual way, running lengthwise. The slats are suspended on springs, which are formed by coiling the two ends of a piece of metal wire spirally, and bending the middle part of the wire into two long curved sides. The spiral coils *a a* are fastened to the head and foot cross-frame of the bedstead by inserting the points of the wire, which are made to project from the coils into holes in the wood, and they are held in place in line with each other by cords, *b b*, which pass through the coils of the springs from one side of the bedstead to the other, as shown clearly in figs. 1 and 2. The curved sides *c c*, which extend from the inner sides of the coils *a a*, lie below the level of the slats B, and on each side thereof, at each end of a slat. On the lower side of the slats B, some distance from each end, are fastened holders or hooks, *d d*, opening towards the ends, for receiving the middle or cross-connecting part of the springs between the long curved sides *c c* in such manner that the slats are held and supported in a level position, as shown clearly in the drawings. By this construction of the springs, with two coils, *a a*, at the ends, and long curved sides, *c c*, their action is compound, the curved sides first receiving the pressure, and gently yielding to it without any sudden or jerking movement before the coils *a a* are affected, but which come in play and support the slats after they pass their centre. The reaction of the springs when the pressure on them is removed is equally easy and pleasant.

Having described my invention, I claim as new, and desire to secure by Letters Patent—

The arrangement of the compound wire springs, having spiral ends, *a a*, attached to the frame of the bedstead A, and held by the cords *b b*; and having also long curved sides, *c c*, connected with the slats B by the hooks *d d*, formed, combined, and operating substantially as and for the purposes herein described.

DAVID MANUEL.
